UNITED STATES PATENT OFFICE.

JOHN J. DONOVAN, OF LYNN, MASSACHUSETTS.

SEWING MACHINE.

Application filed November 3, 1924. Serial No. 747,416.

My invention relates to machine ornamentation, the process or method of producing the same, and the resulting product.

It has for its objects, to provide a new and novel machine design adaptable to a varying combination of colors, simplified for quantity production, inexpensive to produce, and not requiring particular skill on the part of the operator; to extend the field of ornamental machine stitching; to enlarge the scope of ornamentation, making it commercially possible to uniformly decorate any series of articles intended for use in combination for dress or other purposes; to provide a novel means of ornamentation produced with simple equipment without necessity of expensive machinery; to make possible the substitution of machine ornamentation for the hand method now commonly used; to provide an effective means of producing a varying machine ornamentation; to provide a new and novel means of machine embroidery, using a series of needles optionally carrying threads of different colors; to provide an efficient means for cleaning the collet and insuring the uniform positioning of needles therein; to provide a means for the effective and artistic shading and blending of colors in varying ornamental machine design; to provide an artistic ornamentation without injury to, or weakening of the material on which the design is placed; to provide an ornamentation artistic on both sides of the material on which it is placed; and to secure other advantages and results apparent from the following specification.

The process and mechanism by which I accomplish the objects of my invention, involves the placing of specially designed attachments on an eyelet hole finishing machine, said attachments having additional thread carrying mechanism and needles which operate, in conjunction with the thread carrying needle regularly on said machine, in zigzag motion about a circular course. I vary the ornamentation by changing the distance between needles by shimming or otherwise, by color combinations produced by using threads of complementary shades, and by stopping the machine when full, three-quarter, half circles or other segments have been produced, such designs being placed at will where ornamentation is desired. No hole is punched in the material on which the ornamentation

is placed, other than that produced by the small needles used.

Referring to the accompanying drawings which form a part of this specification, Figure 1 is a view of the head portion of an eyelet hole finishing machine with my attachment in place thereon. Figure 2 shows an end view thereof. Figure 3 shows an enlarged detail of my plural needle collet. Figure 4 shows the detail of my improved throat plate. Figure 5 shows the outer needles used with the collet. Figure 6 shows the inner or in between needles. Figures 7, 8, and 9 show varying styles of the ornamentations produced.

Referring again to Figures 1 and 2, A shows the position of the thread spools from which the needles are fed. B shows the thread leads, one for each strand used. C shows the thread tensions, one for each strand. D shows the auxiliary tension used in common by all the strands. E shows the take up lever provided with carrying holes for each strand. F shows the ordinary collar positioned on the needle bar. G shows the collet. H shows the tightening screw on said collet. I, J, and K show the needles positioned in said collet. L shows the throat plate by which the plural needles are properly guided. M shows the threads in their proper position. Referring again to Figure 3, N shows an elongated, narrow, orifice in the collet G in which orifice fits the plurality of needles used. Collet G is provided with a bevel seat at the bottom of the orifice, as shown in Fig. 3, which is designed to insure the same relative position of each needle to the point of the sewing hook at the time the hook arrives at the needle. This is due to the fact that the bevel seat enables certain of the needles to be inserted in the collet further than the others with the result that, when the needles have all been properly positioned in the collet the eyes of the needles will be obliquely disposed with respect to the line of feed, as will be seen in Fig. 1. As the needles come up the sewing hook moves to meet them and the variation is needed to correspond with the time of the hook. By the term "sewing hook" is meant the pointed portion of the shuttle, (not shown), which in the customary operation of the machine oscillates back and forth, engaging the thread in its forward movement, carrying it around the shuttle and thereby crossing the shuttle thread so as to form the

stitch. N^2 shows an opening through the body portion of the collet opposite the bottom of the orifice N to insure easy cleaning of the orifice for accurate alinement of the needles. N^3 shows the holes through which the threads pass before respectively entering the eyes of the needles. I , J , and K show the needles in position in said orifice.

Referring again to Figure 5, T shows the flat inside surface on the head of the outside needles I and K . In Figure 6, V shows the flat surface on both sides of the inside needle J . The flat surfaces on the inside needle and on the inside edges of the outside needles are resorted to for the purpose of more securely holding the needles in position when the tightening screw is set up against them. There may be a varied number of inside needles used, whose shanks are varied according to the space desired between the lines of thread. In the ordinary eyelet machine, the needle bar moves back and forth from right to left, and while the needle is raised from the goods the revolving or rotary feed, in connection with the feed disk, carries the goods in a circular motion which describes the course in which the work moves. It is this circular motion, together with the vertical and lateral reciprocation of the needle, that results in the zig-zag stitching. The revolving presser foot and feed used with the present invention is in large part the same as found on the ordinary eyelet machine but it is modified for the purpose of the invention so as to utilize a multiplicity of needles. The pivot on the throat plate of the ordinary eyelet machine and about which the goods move, is dispensed with in the present invention and the removal of this pivot not only eliminates punctures or holes in the goods but also prevents any crowding of the work or the retarding of the progress of the same, such as would naturally result from the presence of a pivot where the feed operates in a straight line with the feed dog confined in a straight channel cut in the throat plate. As previously explained, the present invention contemplates the use of a circular feed, the goods and feed revolving simultaneously. The throat plate L is provided, as shown in Fig. 4, with a narrow, elongated, slot R through which the multiple needles pass in the stitching process, below and about which is an integral extension S con-

stituting a pilot designed to guide the needles and to insure proper alignment thereof relative to the hook of the shuttle. Figures 8, 9, and 10 show ornamental variations by stopping the operation of the machine at different segments in its circular course.

Similar letters of reference refer to similar parts throughout the various views.

While I have illustrated and described a preferred construction for carrying my invention into effect, this is capable of variation or modification without departing from the spirit of the invention. I therefore do not wish to be limited to the exact details of construction herein set forth but desire to avail myself of such variations and modifications as come within the scope of the appended claims.

Adjustment on the machine, render it possible to change the length of the stitches and vary its frequency in a given space, thus providing for varying the sizes of the ornamental designs produced.

Having thus described my invention I claim as new and desire to secure by Letters Patent of the United States of America:

1. In a sewing machine, a needle bar, a collet carried thereby and presenting an elongated narrow orifice adapted to accommodate a plurality of needles in side by side relation, said collet having a bevel seat adapted to position the needles with the needle eyes obliquely disposed with relation to the plane of the work position, and means for holding the said needles in position.

2. In a sewing machine, a needle bar, a collet carried thereby, said collet having a narrow elongated orifice provided with a bevel seat and having an opening through the body portion thereof opposite the bottom of the orifice, a plurality of needles disposed in the said orifice in side by side relation and engaging the said bevel seat so as to be thereby positioned with the needle eyes obliquely disposed with relation to the plane of the work position, said needles having their relatively abutting sides provided with flat contacting surfaces, and a tightening screw on the said collet adapted to be screwed up against an outside needle for securely holding the said needles in position within the collet.

In testimony whereof I affix my signature.

JOHN J. DONOVAN.
